UNITED STATES PATENT OFFICE.

ARTHUR D. CLOUGH, OF SIERRA MADRE, AND STEFAN ZACSEK, OF LOS ANGELES, CALIFORNIA, ASSIGNORS TO B. B. BELL & CO., OF LOS ANGELES, CALIFORNIA, A CORPORATION OF CALIFORNIA.

ADJUSTABLE FIRE SCREEN.

Application filed June 27, 1924. Serial No. 722,693.

To all whom it may concern:

Be it known that we, ARTHUR D. CLOUGH and STEFAN ZACSEK, citizens of the United States, residing at Sierra Madre and Los Angeles, respectively, in the county of Los Angeles and State of California, have invented new and useful Improvements in Adjustable Fire Screens, of which the following is a specification.

This invention relates to fire screens and consists of the novel features herein shown, described and claimed.

An object is to make a fire screen for mantel fire places which may be easily handled, easily set up and taken down, and which will be effective and satisfactory in operation or use.

Another object is to make a fire screen adapted to form a closure around the open front of a fire place and adapted to be adjusted to and from the fire without losing the closure effect, and the screen having a removable central panel.

Other objects and advantages will appear from the drawings and specification.

The drawings illustrate the construction and operation of a fire screen embodying the principles of our invention.

Figure 1 is a perspective of the fire screen set up for use.

Fig. 2 is a perspective of the fire screen with the central panel removed.

Fig. 3 is a perspective of the central panel of the fire screen.

Fig. 4 is a fragmentary edge view looking in the direction indicated by the arrow 4 in Fig. 3.

Fig. 5 is a perspective of a modified form of the fire screen shown in Fig. 1.

Fig. 6 is a top plan view of the fire screen and a horizontal section of the fire place, the view being taken looking in the direction indicated by the arrow 6 in Fig. 5.

Fig. 7 is a plan of the base shown in Figs. 5 and 6.

Fig. 8 is a perspective of the central panel fitting upon the base shown in Fig. 7.

Fig. 9 is a perspective of one of the end panels fitting upon the base shown in Fig. 7 and as shown in Figs. 5 and 6.

The details of construction and operation shown in the drawings are as follows:

The andirons 1 and 2 have rear legs 3, horizontal supporting bars 4, and front legs

5 and 6. The fire place recess 7 is of considerable size and the andirons are set with the rear legs 3 near the back wall and the front legs 5 and 6 in planes substantially parallel with the back wall.

The end screens 8 and 9 have horizontal lower ends 10 and 11 adapted to fit flat upon the floor 12 and against the face 13 of the wall. Vertical bearings 14 and 15 are formed or built against the rear side of the inner vertical frame bar 16 and similar vertical bearings 17 and 18 extend backwardly from the inner vertical frame bar 19 of the screen 9. An upper spacing bar 20 has downturned pintles at its ends and the pintles fit in the bearings 14 and 17. A lower spacing bar 21 has downturned pintles at its ends and the pintles fit in the bearings 15 and 18. The screens 8 and 9 are adapted to swing upon the pintles of the bars 20 and 21 so as to adjust the bars 20 and 21 towards or away from the plane of the wall 13.

The removable panel 22 is a rectangular frame having upper and lower bars 23 and 24, side bars 25 and 26, and extension frames 27, 28 and 29 extending downwardly from the lower bar 24 with spaces 30 and 31 to receive the supporting bars 4. Hooks 32 and 33 extend backwardly and downwardly from the bar 25 and similar hooks 34 and 35 extend backwardly and downwardly from the bar 26. Handles 36 and 37 extend upwardly from the upper corners of the frame so that the handles 36 and 37 may be grasped and the panel 22 raised and placed in position with the side bars 25 and 26 engaging the side bars 16 and 19 and the hooks 32, 33, 34 and 35 engaging the spacing bars 20 and 21.

The screen thus constructed is adjustable by moving the panel 22 to or from the plane of the wall 13 and swinging the screens 8 and 9 outwardly or inwardly along the face of the wall. The screens 38, 39 and 40 and the screen extension frames 27, 28 and 29 may be any desired form or quality of woven wire and may be ornamented as desired to make a good appearance. To have access to the fire it is only necessary to grasp the handles 36 and 37, raise the hooks from the bars 20 and 21 and move the panel 22 laterally or entirely out of the way to apply the fuel and fix the fire.

The details of the modified construction

shown in Figs. 5, 6, 7, 8 and 9 are as follows:

The fire place 50 has a back wall 51, a floor 52 on a level with the floor 53 of the room, and side walls 54 and 55, and the wall faces 56 and 57 extend laterally from the front of the fire place.

A base 58 is formed of flat sheet metal adapted to lay upon the floor 52 and 53 and 10 has a straight central portion 59 and end portions 60 and 61 extending from the ends of the portion 59 at angles of about 30°. Channel shaped sockets 62 and 63 are fixed to the ends of the intermediate portion 59 15 and extend upwardly a short distance with the channels facing each other. Similar channel sockets 64 and 65 are fixed to and extend upwardly from the end portion 60, and a third pair of channel sockets 66 20 and 67 are fixed to and extend upwardly from the portion 61.

The end screens 68 and 69 have pintles 70 and 71 extending upwardly from their upper inner corners and have supporting bars 25 72 and 73 at their lower ends. Each supporting bar consists of a channel shaped socket 74 at its center and adapted to receive tightly a lower end bar 75 of the screen and feet 76 and 77 extending outwardly a considerable distance and engaging the floor at their outer ends so as to brace the screen and hold it upright. The sockets 74 are sufficiently elevated to pass over the base 58 with the feet 76 and 77 resting upon 30 the floor and the ends of the bars 75 engaging in the sockets 64 and 65 and 66 and 67.

The central screen panel 78 is a rectangular frame having slots 79 and 80 extending upwardly from its lower edge to receive the 40 andiron supporting bars 81 and 82. The lower corners of the frame of the panel fit in the sockets 62 and 63. Arms 81 and 82 extend from the upper corners of the panel and have pairs of prongs 83 and 84 extending downwardly from their outer ends to straddle the upper ends of the screens 68 and 69, there being pintle openings 85 and 86 between the prongs 83 and between the prongs 84 to receive the pintles 70 and 71. 45 Handles 87 and 88 extend upwardly from 50

the corners of the panel so that by grasping the handles 87 and 88 the central panel may be elevated and removed to attend to the fire.

The outer corners 89 and 90 of the base 55 58 are cut away to form runners or guides to engage loosely between the faces 54 and 55 of the fire place so that the screen may be moved bodily backwardly or forwardly to adjust the screen relative to the fire place. 60

Various changes may be made without departing from the spirit of the invention as claimed.

We claim:

1. A fire screen having end screens, means 65 for holding the end screens upright, and a central panel fitting between the end screens and adapted to be removed.

2. A fire screen having end screens, means 70 for holding the end screens upright and a central panel fitting between the end screens, having upwardly extending recesses formed therein, adapted to extend over the horizontal bars of andirons and adapted to be removed.

3. A fire screen comprising end screens, 75 a pair of bars connecting said end screens and a removable panel having upwardly extending recesses formed therein, adapted to extend over the horizontal bars of andirons 80 and rest on the floor.

4. A fire screen adapted to form a closure 85 around the open front of a fire place, comprising end screens, horizontal bars pivotally connecting said end screens and a removable panel having hooks adapted to engage said pair of horizontal bars.

5. A fire screen adapted to form a closure 90 around the open front of a fire place, comprising end screens, horizontal bars pivotally connecting said end screens and a removable panel having hooks adapted to engage said pair of horizontal bars, and having upwardly extending recesses formed 95 therein adapted to extend over the horizontal bars of andirons.

In testimony whereof we have signed our names to this specification.

ARTHUR D. CLOUGH.
STEFAN ZACSEK.
